UNITED STATES PATENT OFFICE.

LOUIS H. WOODCOCK, OF COLVILLE, WASHINGTON.

FLY SWITCH.

Application filed April 16, 1923. Serial No. 632,523.

To all whom it may concern:

Be it known that I, LOUIS H. Woodcock, a citizen of the United States of America, residing at Colville, Stevens county, State 5 of Washington, have invented new and useful Improvements in Fly Switches, of which the following is a specification.

This invention pertains to fly-switches and has for its object to provide an improved 10 holder for the switch portion, whereby the switch portion is removable and interchangeable, in order that when the switch portion becomes too badly worn for use, the same may be removed and replaced by another 15 one.

The invention will be hereinafter particularly described and illustrated in the accompanying drawings, in which:

Figure 1 is a view of the improved holder 20 complete, with the switch portion in place and secured therat.

Figure 2 is a view of the outer end of the frame of the holder, broken-away, shown in position for receiving the switch portion.

25 Figure 3 is a view of the outer end of the frame of the holder, broken-away, together with a view of the switch portion, broken-away, and showing the manner of securing the switch portion to the holder and Figure 4 is an enlarged detail view of a means 30 for rigidly securing the parts together.

In a detail description, in which like numerals refer to like parts throughout the several views, the holder consists of two 35 pieces of wire 10 and 11, a portion of each being formed into a loop 12 and 13 respectively, the two loops being hinged together at approximately the center thereof, by the formation of offsets 14 in the wire 40 of the loop 12 and the formation of loops 15 in the wire of the loop 13, such loops engaging the offsets 14.

The ends 16 and 17 of the wire 10 are 45 formed into inwardly turned points by crossing and over-lapping the wire 10 at the outer end of the loop 12 as at 18 and by bending over or looping the wire as at 19 and 20.

A handle is provided for the holder by forming a loop 21 in the wire 10 at the end 50 of the holder opposite the loop 12, the latter loop being formed by the twisting of the wire 10, as at 22.

A plate 23 is secured to the outer end of the loop 13 and fastened as by wrapping the plate 23 over the wire 11 at the points 55 24, 25 and 26. The ends 27 and 28 of the wire 11 are formed into oppositely disposed catches 29 and 30 by the twisting of the wire 11, as at 31 and bending the wire as 60 shown. The switch 32 is placed between the loops 12 and 13 and the loops brought together by engaging the catches 29 and 30 over the twisted portion 22 of the wire 10, whereby the switch 32 is firmly clasped 65 between the loops 12 and 13 and held firmly by means of the points 16 and 17 penetrating the mesh of the switch 32, as at 33, the points 16 and 17 bearing against the plate 23. In order to prevent the marring of the paint 70 or varnish on woodwork when striking at flies with the holder, the wires 10 and 11 are wrapped with tape 34 at the proper places, which tape is secured in place by means of rivets 35 or by such other means 75 as may be desired.

What is claimed is:

A fly-switch holder comprising a pair of wire clamps, the two being hinged together in such a fashion as to form a pair of loops 80 at one end, the outer end of one of said loops being provided with inwardly extending pins and the outer end of the other of said loops being provided with a plate 85 extending across such loop directly opposite said pins, between which pins and plate the switch is to be held and the other end of said clamps formed into a handle and means at the handle end for interlocking the two parts together to hold said switch firmly 90 in place between said loops.

In testimony whereof, I affix my signature.

LOUIS H. WOODCOCK.
